AUTOGRAPHIC REGISTER

Harry J. Waechter, Mount Healthy, Ohio, assignor to Paul Benninghofen and Fritz G. Diesbach, Hamilton, Ohio, as trustees

Application February 20, 1941, Serial No. 379,851

7 Claims. (Cl. 282—16)

This invention relates to manifolding or continuous form stationery of the type utilized in autographic registers and to the mechanism of these registers for feeding, aligning, and delivering the forms. More particularly, this invention is directed to improvements in manifolding stationery which comprises a plurality of superimposed forms of the type utilized in autographic registers, and to the cooperating feed mechanisms of these registers; whereby various lengths of forms, within practical limits, may be fed and positively aligned during the feeding operation without changing the feeding mechanism to suit the various lengths of forms. In other words, by utilizing the present invention, one standard feed mechanism is provided to feed and maintain in positive registry, forms of different lengths.

Thus, it has been an object of the present inventor to provide an autographic register and manifolding stationery for this register whereby accurate and positive alignment of the forms is made during every feeding operation and to provide the register with a set of compensating feed rolls for cooperation with corresponding apertures in the superimposed forms so that the one mechanism can be employed to feed, align, and dispense forms of widely varying lengths.

The present inventor has provided an autographic register which utilizes cooperating sets of discs or rolls, upper and lower, to feed and align the improved forms by virtue of their feeding relationship to apertures in the forms. The rolls are manually operated by a crank which is fixed to one end of the shaft carrying the lower set of rolls. The upper rolls are in positive transmission connection with the lower rolls by gears, and are carried on a common shaft which is spring urged to provide a peripheral contact between the two sets.

An embodiment of this invention may incorporate three sets of rolls or discs. One set engages the strips midway of their widths, and the others engage the margins of the strips. The outer discs or rolls include treads of very short length for initially starting the feed. The central disc or roll includes an almost continuous tread portion with the exception of a relieved portion at which point the paper is advanced by direct engagement in a central aperture in the paper. The circumferential dimension of the tread portion of the central roll is sufficient to feed the longest form employed. The feed will terminate when the apertures are disposed between the center rolls, whereupon the center rolls idle, and feed stops until cams on the outer disc are effec-

tive for raising the upper rolls to relieve the paper of feeding contact from the rolls, whereupon a pin, projecting from the center roll at the relieved portion, advances and aligns the strips in the final phase.

The strips making up the successive packs of sales forms include weakened tear-off lines defining the sales forms or slips. Each form includes one aperture, which aperture is located back of the tear-off line in each form and centrally of the width of the forms. No other apertures in the paper are required.

The superimposed strips are fed through the rolls continuously in the following phases of operation. In the first phase or the starting phase, the tread surfaces of the outer or marginal rolls or discs are effective for moving the paper forwardly to a point where the tread portion of the center or compensating feed roll may take hold. Thereupon, the strips are fed by means of the center roll. This phase may be referred to as the compensating phase since strips of any length, within the limits established by the circumferential dimension of the central tread, may be fed until their apertures are disposed between the rolls; whereupon feed ceases and the center roll idles. Toward the end of the complete rotation of the center roll, cams on the outer disc are effective for raising the upper roll and clearing the paper of contact between the rolls, whereupon a pin on the center roll enters the apertures and advances the paper in a final short feeding and aligning phase. At this time, the pin moves into the aperture and advances the strips by direct engagement with the forward walls of the apertures, thus aligning all the strips and disposing the advanced forms for tear off.

The manifold pack or continuous form stationery disclosed in this application is disclosed and claimed in a copending divisional application filed Dec. 30, 1942, and bearing Serial No. 470,601.

Other objects and certain advantages of the present invention will be more fully apparent from a description of the accompanying drawings, in which:

Figure 1 is a perspective view of an autographic register embodying the present invention.

Figure 2 is a perspective view similar to Figure 1, in which the cover has been lifted back to expose the feeding mechanism and the writing platen, the stationery having been removed.

Figure 3 is a longitudinal sectional view taken on line 3—3, Figure 1.

Figure 4 is a sectional view taken on line 4—4, Figure 3, illustrating the feed rolls.

Figure 5 is a plan view of a length of the strips showing a complete form and illustrating the arrangement of the aperture therein.

Figure 6 is a sectional view taken on the line 6—6, Figure 4, illustrating the center or compensating feed roll in position at the end of the final feeding and aligning movement.

Figure 7 is a sectional view taken on line 7—7, Figure 4, illustrating one of the marginal rolls or discs in the same relative position as the compensating disc and in position to start the feed of the strips through its short tread portion.

Figure 8 is a sectional view taken on line 8—8, Figure 4, illustrating a marginal feed roll or disc in position with its cam elevating the upper roll to relieve the strips of contact between the rolls just prior to the final advancing or aligning phase of movement of the strips.

The continuous strips of forms illustrated here form a part of the present invention and consist of lengths of paper providing forms 11 defined by weakened, transverse tear lines 12. An aperture 13 is provided centrally of each form and spaced back of the tear-off line at the head end of the forms. These apertures are engaged by the aligning pin and also cooperate with the compensating rolls.

Referring to the drawings, 15 indicates the casing of an autographic register providing an interior compartment 16 for a supply of zig-zag folded manifold forms 17 and a storage compartment 18 for receiving in refolded condition one of the strips for record purposes. This latter compartment, however, may be omitted where all strips of the pack are to be delivered from the machine. The strips are fed over a writing table or platen 19 which is disposed within the casing above the supply compartment. The platen 19 is hinged as at 20 at its rear edge to the side walls of the casing and is adapted to be swung upwardly for access to the compartment 16. The platen rests on a lip 21 turned inwardly from the wall of the casing on one side, and on the top edge of an internal wall 22 on the other side.

The feeding or translating rolls are operated by a crank handle 23 pinned to one end of a shaft 24 which carries the lower rolls. The crank is limited normally to a single continuous cycle of operation by a pair of spring-urged push pins extending from the side wall of the casing to interlock with the crank handle. Only one of these pins is shown at 25. When the handle is locked against rotation, the push pin, as a stop or limit against further rotation of the handle, is exposed and is accessible to the operator. By depressing the pin, the handle is released for a successive or subsequent cycle of operation. This type of stop or its equivalent is well known in the art and further illustration and description is believed unnecessary.

The strip feeding mechanism includes a set of upper rolls comprising an upper feeding or translating roll 26 at each side, and the long, upper compensating or adjusting feed roll 27 disposed between the rolls 26, 26. The upper rolls are carried on a common shaft 28 which is journaled in vertical slots 29 in an elongated journal box 30. The shaft is urged downwardly by means of coil springs 31—31 seated under compression in the journal box above the vertical slots. A pair of seats 32—32 provides for exertion of the spring pressure on the shaft. The journal box is fixed upon a cross section of a frame 33 which covers the top of the machine in a slightly ele-

vated position from the writing table. The frame is provided with an opening for exposing a form section of the strip upon the platen and is hinged at its forward end to the casing so that it can be swung upwardly for access to the writing table for loading the machine.

The lower rolls are substantially larger than the upper rolls and include a pair of outer feeding rolls or discs 34—34 and a central adjusting or compensating feed roll 35. The shafts upon which the upper and lower rolls are carried are in positive transmission connection through meshing pinions 36—37. The compensating feed roll is mounted on the shaft 24 medially between the two outer feed rolls. The feed roll 35 carries a pin 38 formed integrally therewith and projecting radially from a flattened or recessed portion 39 of the roll. The adjusting or compensating feed roll 35 has a continuous tread 20 with the exception of the relieved portion containing the pin. Thus, it is continuously effective after the strips have been initially started for feeding the paper until it has fed the strips to bring the centrally located apertures in registry between it and its upper roll.

The outer feed rolls or discs 34 provide tread portions 40, consisting of flanged elements fixed to the inner sides of the discs and providing arcuate tread surfaces appropriately spaced diametrically on the disc for engaging the paper against the upper roll to bring about a short starting feed. Apart from this tread portion, the outer discs are not effective in the feed. They guide the strips since they extend above and engage the side edges of the strips. These portions 40 are effective, as shown in Figure 7, for clamping the paper between the portions and the upper roll, whereby the advanced forms may be torn off without displacing the strips.

40 Toward the end of the feed when the pin on the center roll is about to enter the apertures, cam portions 41 on the discs engage the upper roll to raise the same to clear the paper so as to permit free movement of the paper under the influence of the pin as it shoves the paper forwardly. These cam portions may be formed by punching through the metal disc to force a portion of the metal outwardly to create a hump on the periphery of each disc.

50 The platen dips down or is recessed to fit the contour of the upper feed roll just below the upper feed roll (Figure 6). Leaf springs 42 fasten to the underside of the lid, providing curved ends engaging the top of the strips and holding them in the recess and, therefore, upon the aligning pin as the pin moves into the apertures.

Operation

As illustrated in Figure 6, the mechanism is disposed at the end of a feeding cycle. It will be noted that the pin 38 is engaged against the forward margins of the apertures of the paper, and there is no engagement of the paper between the central roll and the upper roll. Now, as the operator starts the rotation of the crank, the treads 40 on the outer discs engage the paper against the upper roll, and the paper is fed slightly through this engagement. In fact, it is fed enough to bring the beginning of the tread portion of the center disc into contact with the paper, whereupon the center disc continues the feed.

The compensating roll will continue to feed the strips until the central apertures move into position between the compensating rolls. The

balance of the movement of the center roll is idle, and the strips remain where they are until the cam portions of the discs engage the upper roll and raise it out of contact with the paper. At this point, the pin 38 is entering the apertures and engaging the forward walls thereof. All contact with the strips has been terminated at this point due to the recessed portion of the central disc; in fact, the short starting treads have not come up to contact. Therefore, the paper is pulled forward easily by the pin and is aligned by engagement with the forward face of the pin.

Having described my invention, I claim:

1. In an autographic register, a platen over which continuous strips of sales forms are adapted to be fed, said sales forms including feeding and aligning apertures located centrally of the width of the strips at the head end of each form, upper and lower feeding rolls between and by means of which said strips are adapted to be fed, one lower roll engaging the strips centrally in alignment with the apertures and including a continuous tread portion with the exception of a recessed portion, a starting pin extending radially from said recessed portion and adapted to engage in the apertures for aligning the same, the outer lower rolls adapted to engage the side edges of the strips and including short tread portions disposed for engagement with the strips just ahead of engagement of the strips by the tread portion of the central roll, said outer rolls including cams on their peripheries adapted to spread the rolls for relieving the strips of contact as the pin enters the apertures.

2. In an autographic register, a platen over which continuous strips of sales forms are adapted to be fed, said sales forms including feeding and aligning apertures located centrally of the width of the strips at the head end of each form, upper and lower feeding rolls between and by means of which said strips are adapted to be fed, one lower roll engaging the strips centrally in alignment with the apertures and including a continuous tread portion with the exception of a recessed portion, a starting pin extending radially from said recessed portion and adapted to engage in the apertures for aligning the same, the outer lower rolls adapted to engage the side edges of the strips and including short tread portions disposed for engagement with the strips just ahead of engagement of the strips by the tread portion of the central roll.

3. An autographic register of the type including a platen over which superimposed strips of continuous form paper are adapted to be moved, comprising an upper pressure roll and a lower set of feeding rolls engaging the strips therebetween, each form of the strips including one aperture therein, located centrally of the form and adjacent the tear-off line at the head end of the form, one roll of the lower set of feeding rolls constituting a compensating feed roll and including a periphery having a tread portion extending entirely around the roll with the exception of a relieved portion, a pin carried by said latter roll projecting radially from the relieved portion of the roll and adapted to engage the apertures at the end of the feeding rotation of the roll, and said lower set of feeding rolls including outer rolls, said outer rolls having tread portions extending a short distance around the rolls and starting at a point just ahead of the point at which the tread portions start on

the compensating feed roll whereby after the outer rolls have advanced the strips a starting distance, the compensating feed roll continues to engage the strips and feeds them until the central aperture is disposed between the compensating feed roll and the upper roll and they engage through it for purposes of alignment whereupon the compensating feed roll and the upper roll idle until the pin enters the apertures and finally advances and aligns the strip, said outer feeding rolls including cam portions raising the upper roll for disengaging the strips when the pin enters the apertures.

4. In an autographic register, a platen over which continuous strips of sales forms are adapted to be fed, an upper pressure roll and a lower set of feeding rolls adapted to engage the continuous strips therebetween for feeding the strips, one roll of the lower set of feeding rolls having a substantially continuous tread surface extending entirely around its periphery with the exception of a short clearance portion, said tread surface adapted to register with apertures in the strips for idle movement when the apertures are reached, another roll of said lower set of feeding rolls providing a tread surface of much shorter length than the tread surface of the first-named lower feeding roll, but starting at a point just ahead of the start of the tread surface of the first-named lower feeding roll, and a pin extending from the short clearance portion of the first-named lower feeding roll, engageable in the apertures in the strips for completing the feed of the strips and aligning the apertures.

5. In an autographic register, a platen over which continuous strips of sales forms are adapted to be fed, an upper pressure roll and a lower set of feeding rolls adapted to engage the continuous strips therebetween for feeding the strips, one roll of the lower set of feeding rolls having a substantially continuous tread surface extending entirely around its periphery with the exception of a short clearance portion, and another one of said lower set of feeding rolls providing a tread surface of much shorter length than the tread surface of the first-named lower feeding roll, said shorter tread surface starting slightly in advance of the starting point of the tread surface of the first-named lower feeding roll, a pin on the first-named lower feeding roll projecting radially from the relieved portion for engagement in central apertures in the strips and a cam formed on the last-named lower feeding roll for spreading the upper pressure roll and the set of lower feeding rolls when the pin engages the apertures.

6. In an autographic register, a platen over which continuous strips of sales forms are adapted to be fed, said sales forms including feeding and aligning apertures located centrally of the strips in each form, an upper pressure roll and a lower set of feeding rolls between and by means of which said strips are adapted to be fed, one of said lower set of feeding rolls disposed in alignment with the central aperture and having its tread portion extending substantially entirely around its periphery with the exception of a short clearance, outer ones of said lower set of feeding rolls including short tread portions starting just in front of the tread portions of the first-named lower feeding roll and a starting pin projecting radially from the clearance portion of said first-named lower feeding roll, whereby the first-named lower feeding roll will continue to feed the strips until the central

apertures of the strips are disposed between it and the upper pressure roll and feeding contact ceases between the central roll and the strips and whereupon the feed will be continued for an aligning period when the pin of the first-named lower feeding roll engages the apertures of the strips.

7. In an autographic register, a platen over which continuous strips of sales forms are adapted to be fed, said sales forms including feeding and aligning apertures located centrally of the strips, an upper pressure roll and a lower set of feeding rolls between and by which said strips are adapted to be fed, said lower set of feeding rolls including a central feed roll disposed for registry with the central aperture having its tread portion extending substantially en-

tirely around its periphery with the exception of a short clearance, outer ones of said lower set of feeding rolls having short tread surfaces engage the strips just ahead of the tread surface of said 5 first-named lower feeding roll, and a starting pin projecting radially from the clearance of said first-named lower feeding roll, whereby the first-named lower feeding roll will continue to feed the strips until the central apertures of the strips 10 are disposed between the upper pressure roll and said first-named lower feeding roll and feeding contact ceases between the first-named lower feeding roll and the strips and whereupon the feed will be continued for an aligning period 15 when the pin engages in the apertures.

HARRY J. WAECHTER.
